UNITED STATES PATENT OFFICE.

HUGH SWARTZ AND PAUL C. MULLIGAN, OF SEATTLE, WASHINGTON, ASSIGNEES TO
DUAL OIL BURNER, INC., OF SEATTLE, WASHINGTON.

OIL-BURNER SYSTEM.

Application filed July 17, 1926. Serial No. 123,170.

Our invention relates to improvements in oil burning systems and the objects of our invention are to provide an oil burning system that is highly efficient in operation and 5 that is comparatively cheap and simple to install.

Another object is to provide an oil burning system in which a single air pump is made to perform the double function of lifting the oil by suction from an underground storage tank to a vacuum tank and of drawing the oil by suction from the vacuum tank to a discharge nozzle, the discharge nozzle being at a higher elevation than the oil level 15 in the vacuum tank.

A further object is to provide an oil burning system which has an oil conduit between the vacuum tank and the air pump so that a small portion of the fuel oil will be constantly drawn through the pump, keeping the pump thoroughly lubricated at all times.

Further objects reside in the provision of novel spray nozzle and ignition means.

Other and more specific objects will be apparent from the following description taken in connection with the accompanying drawings.

In the drawings, Figure 1 is a somewhat diagrammatic view partly in section and 30 partly in side elevation of an oil burning system constructed in accordance with our invention.

Figs. 2, 3, and 4 are detached sectional views on a larger scale of a vacuum tank, 35 a fuel discharge nozzle and a spark plug used for ignition purposes respectively.

Referring to the drawings, throughout which like reference numerals designate like parts, 5 designates any furnace or similar device which is to be heated and 6 designates a combustion tube that is inserted through the side of the furnace. A fuel discharge nozzle embodying an outer nozzle member 7 and an axially disposed inner injector member 8 is screwed into the end of the combustion tube 6 as shown in Fig. 3. The outer nozzle member 7 has an internal recess 10 of larger diameter than the exterior of the injector member 8 and said nozzle member 7 is provided with a discharge orifice 11. A fuel inlet pipe 12 is tapped through a head 13 on the outer end of the nozzle member 7 and communicates with the internal passage way 10 surrounding the injector member 8. A pipe 13 for the inlet of air under pressure

is connected with the outer end of the injector member 8 and adapted to discharge air through a relatively small axial bore 14 in said injector member 8.

Fuel discharging from the nozzle 7 may be ignited by a spark plug 15 that is threaded through one side of the combustion tube 6 and has terminals 16 positioned so as to produce a spark or sparks in the path of discharge of the fuel directly in front of the nozzle 7. To prevent carbonizing of the spark plug terminals 16 we provide air inlet passageways 17 in the upper portion of the spark plug and further provide one or more air inlet openings 18 in the wall of the combustion tube 7, all of said air inlet openings being arranged to have cold air drawn in therethrough over the terminals 16 thus preventing the formation of carbon on said terminals. Any suitable manually or automatically operated means may be provided for controlling the discharge of sparks from said spark plug. The tube 6 together with associated parts constitute an efficient burner head that may be used for spraying fuel into any type of oil burning furnace.

The air inlet pipe 13 is connected with the air discharge port of a rotary air compressor or pump 20. The fuel inlet pipe 12 has a valve 21 interposed therein and is connected with the bottom end of a vacuum tank 22. The air inlet port of the rotary pump 20 is connected by a pipe 23 with the upper end of the vacuum tank 22 and said pipe 23 is further provided with valve controlled means indicated at 24 that opens to the atmosphere so that air may be admitted to the pump 20 and at the same time a vacuum maintained in the upper portion of the vacuum tank 22. An oil conduit pipe 25 for lubricating oil is connected with the air inlet pipe 23 and with the bottom of the vacuum tank 22 to supply oil for lubricating the pump 20. A valve 26 is provided in the pipe 25 to control the amount of oil 100 for lubricating purposes that is allowed to pass to the pump 20.

The pump 20 may be driven by a motor 27. The vacuum tank 22 is of standard construction, having an upper compartment 28 connected by a tube 29 with a lower compartment 30. A check valve 31 is provided in connection with tube 29. A vent pipe 32 connects lower compartment 30 with the atmosphere. A float 33 is provided in the 110

upper compartment 30 and is adapted to open and close a valve 34 within a passage-way 35 that communicates with the outside atmosphere. The upper compartment 28 is connected by a pipe 36 with a fuel storage tank 37 usually located underground and at some distance from the vacuum tank. A vent 38 is ordinarily provided for the fuel storage tank 37.

13 The vacuum tank 22 is positioned so that the maximum level of the fuel therein as indicated at 40 is below the horizontal plane of the burner nozzle 7. This absolutely prevents a gravity flow of fuel from the vacuum tank out of the burner nozzle under any conditions.

14 In the operation of this oil burner system the motor 27 driving the pump 20 discharges air through the pipe 13 and nozzle tube 8 as shown in Fig. 3 and at the same time induces a vacuum or suction in the upper vacuum tank compartment 28. This suction closes the check valve 31, and, if valve 34 is closed, draws fuel from the storage pipe 36. 25 As soon as the fuel level in the compartment 28 raises the float 33 high enough to open the valve 34 the suction in the compartment 28 is relieved, the check valve 31 is allowed to open and fuel flows down through the 30 tube 29 into the lower vacuum tank compartment 30. When the float 33 has been lowered sufficiently it again closes the valve 34 and more fuel is drawn into the upper compartment. By operating in the manner 35 common to vacuum tanks of this nature the fuel level in said vacuum tank is automatically maintained between two limits determined by the upper and lower limits of the float 33 in opening and closing the valve 34. 40 The discharge of air through the injector tube 8 produces a suction in the fuel inlet pipe 12 sufficient to draw oil or similar liquid fuel from the tank 22 into the chamber 10 of the fuel nozzle, from which said oil is 45 drawn outwardly past the end of the injector pipe 8 and discharged in a finely divided spray along with the air from the discharge orifice 11.

46 The spark plug 15 is caused to deliver a 50 spark or sparks into the sprayed fuel to ignite the same. The cold air drawn in through the openings 17 and 18 prevents the formation of carbon on the spark plug terminals, on the end of the nozzle and within 55 the adjacent parts of the combustion tube 6.

56 Combustion begins within the combustion tube 6 but occurs chiefly beyond the end of

said tube and in the combustion chamber of the furnace.

57 The relative amounts of oil and air that 60 are delivered through the nozzle may be regulated by adjustment of the valve 21.

58 When the motor is stopped suction on pipe 21 will cease, and, consequently, the flow of fuel will cease, the nozzle 7 being slightly 65 above the plane of the fuel level 40 in the vacuum tank making it impossible to flood the furnace by a gravity flow of oil in case of accidental stopping of the mechanism.

60 An important feature of the invention resides in the novel arrangement of rotary air 70 pump, vacuum tank, and connections therebetween by which the air pump is made to perform the three fold duty of furnishing air under pressure for the burner, drawing 75 fuel by suction into the vacuum tank and drawing oil for its own lubrication from the vacuum tank.

65 Another important feature of the invention is in the provision of the control means 80 that enables a limited amount of suction to be maintained upon the intake manifold and at the same time permitting sufficient air to provide a pressure for operating the oil 85 burner spray nozzle.

66 The following description and accompanying drawings clearly disclose a preferred embodiment of our invention, but it 90 will be understood that this disclosure is merely illustrative and that such changes 95 in the apparatus may be made as are within the scope and spirit of the following claim.

67 What we claim is:

68 In oil burning apparatus of the class described, an injector type burner head, a vacuum tank having a vacuum chamber and an oil storage chamber, an air pump, means for 95 driving said air pump, a conduit connecting said burner head with the air discharge port of said pump, another conduit connecting 100 said burner head with the oil storage chamber of said vacuum tank, another conduit connecting said vacuum chamber with the suction inlet of said pump, another conduit connecting the suction inlet of said pump 105 with said oil storage chamber for supplying oil for lubricating purposes to said pump, an oil storage tank and a conduit pipe connecting said vacuum chamber and said oil storage tank.

110 In witness whereof, we hereunto subscribe our names this 12th day of July, A. D. 1926.

HUGH SWARTZ.

PAUL C. MULLIGAN.
